UNITED STATES PATENT OFFICE.

THOMAS J. MACKENZIE, JR., OF PHILADELPHIA, PENNSYLVANIA.

LATCH.

1,412,363.

Specification of Letters Patent. Patented Apr. 11, 1922.

Application filed May 12, 1921. Serial No. 468,922.

To all whom it may concern:

Be it known that I, THOMAS J. MACKENZIE, Jr., a citizen of the United States, residing at Philadelphia, in the county of 5 Philadelphia and State of Pennsylvania, have invented certain new and useful Improvements in Latches, of which the following is a specification.

One object of my invention is to provide 10 an improved latch which can be used with advantage on automobile doors or doors of other types and which can be operated by the movement of a plunger.

A further object is to provide a latch of 15 a simple and durable construction which can be quickly and easily manufactured and installed.

These objects, and other advantageous ends which will be described hereinafter, I 20 attain in the following manner, reference being had to the accompanying drawings in which

Figure 1 is a sectional side elevation showing a latch made in accordance with my invention,

Figure 2 is a section taken on the line 2—2 of Figure 1,

Figure 3 is a view of the same general character as that shown in Figure 1 illustrating the parts in another position when the bolt of the latch is withdrawn, and

Figure 4 is a view of the same general character as shown in Figures 1 and 3 illustrating the parts in still another position.

Referring to the drawings, 5 is a rectangular casing in which the side 6 is preferably made detachable so as to permit access to the interior of the casing. A bolt 7 is slidably mounted within the casing; the rear end 8 being positioned within guideways 9; the forward end portion 10 of said bolt having a horizontally extending slot 11 through which extends a cylindrical lug 12 which may be made integral with and projecting

45 forwardly from the back 13 of the casing 5. Thus the lug 12 and the guideways 9 serve to form a sliding bearing for the bolt. The forward end 14 of the bolt is beveled and is adapted to move through a hole 15 in 50 the front end 16 of the casing 5. A cam 17 is freely rotatable on the lug 12 and in the

present instance has four pins 18 projecting from the side thereof and spaced apart around the axis of the lug 12. The rear part 8 of the bolt 7 has a lateral projection providing two slanting surfaces 19 and 20 which are in the plane of the cam 17; said surfaces terminating in a point 21. The cam 17 has opposed edge surfaces 22 each having a slight depression 23 which merges with two 60 slightly convex portions 24 and 25. The surface portions between the portions 22 are made with a comparatively deep depression 26 which merges with substantially flat surface portions 27 and convex portions 28. 65

A plunger 29 extends through a hole in the top 30 of the casing 5; said plunger having a slot 31 through which a lug 32 on the casing extends so that the plunger will be guided in a straight path. The lower end 70 33 of the plunger is preferably slightly tapered and this end is normally held out of the path of the pins 18, as shown in Figure 1, by a spring 34; said spring being looped and having one end bound around the lug 75 32 and the other end secured to a lip 35 on the plunger. The plunger 29 preferably has a top section 36 which is screwed to the lower section; said top section being rounded to provide a push button 37. The arrangement is such as shown in Figure 1 that when the bolt is projected with its beveled end 14 out of the casing that the point 21 of the bolt is positioned within one of the depressions 26 of the cam and with one of the pins 80 18 directly under the end 33 of the plunger. A spring 38 within the casing engages the part 8 of the bolt and normally tends to move and hold the bolt in its projected position. 85

The casing 5 can be inserted in a door such for example as an automobile door with the button 37 in a position where it can be pushed by the finger of a person and when it is desired to open the door the plunger is 95 depressed so as to cause the lower end of the plunger to engage said latter mentioned pin and to turn the cam 17. This action will cause the adjacent surface portion 27 of the cam to engage the surface 19 of the bolt and owing to the angular or slanting disposition of this surface the bolt will be retracted un- 100

der the pressure of a person's finger until the adjacent surface portion 25 moves into engagement with the point 21 of the bolt, after which the spring 38 will move the bolt a short distance outward and at the same time due to the curved character of the surface portion 25 of the cam, as shown in Figure 3, the cam will be rotated from the position shown in Figure 3 to the position shown in Figure 4 until the adjacent depression 23 of the cam moves into registry with the point 21 of the bolt and since the point 21 is in line with the axis of the lug 12, upon which the cam is rotatably mounted, the bolt will be held in the position shown in Figure 4 after having moved a short distance outward from the position shown in Figure 3. It will be noted however that the portion 14 of the bolt will still be within the confines of the casing 5 and when the latch is within a door and the bolt is in said latter mentioned position the door can be freely opened and the bolt will remain in this position until the plunger 29 is again moved downward during which action the lower end 33 of the plunger will strike another of the pins 18 and will rotate the cam until the surface portion 28 engages the point 21 of the bolt, after which the action of the spring 38 will move the bolt and will also rotate the cam until the adjacent deep depression 26 moves into registry with the point 21; it being noted that the spring 38 will cause the point 21 to follow on the cam and during this action the part 14 of the bolt will be projected out of the hole 15 into its retaining position where it will engage the keeper on the frame of the door. The spring 34 serves to raise the plunger into its normal position after the pressure of a person's finger has been removed therefrom and this upward movement of the plunger permits the next pin in the cycle of rotation to pass into a position below the end 33 of the plunger so that when the plunger is again depressed the quarter turn movement of the cam will be effected partly by the action of the plunger and partly by the action of the spring 38.

The spring 38 is in the form of a loop extending around another lug 39; one portion of the spring 38 being in engagement with the bolt while the other portion abuts the inner surface of the end of the casing. The side 6 of the casing is attached by screws 40 which fit in tapped holes in the various lugs 12, 32 and 39 so that the parts are kept in position between the side 6 and the back 13.

While I have described my invention as taking a particular form, it will be understood that the various parts of my invention may be changed without departing from the spirit thereof, and hence I do not limit myself to the precise construction set forth, but consider that I am at liberty to make such

changes and alterations as fairly come within the scope of the appended claims. 65

Having thus described my invention, what I claim as new and desire to secure by Letters Patent is:—

1. A latch including a bolt; a plunger; 70 and means operative by the plunger in successive movements thereof in the same direction for effecting movement of said bolt into and out of locking position; substantially as described. 75

2. A latch including a bolt; a cam for engagement with the bolt and having a plurality of actuating portions; and a plunger operative to successively move said cam portions to effect movement of said bolt; substantially as described. 80

3. A latch including a bolt; a cam for operative engagement with said bolt; pins on said cam spaced apart; and a plunger movable successively into engagement with said pins whereby movement of the cam is effected to actuate the bolt; substantially as described. 85

4. A latch including a slidable bolt; a rotatable cam, said bolt having a portion 90 movable toward and from the axis of said cam, said cam having depressions therein in which said portion of the bolt is adapted to engage; pins projecting from said cam; a spring for holding said portion of the bolt in engagement with the cam; and a plunger operative to successively engage said pins and thereby intermittently move said cam to effect movement of the depressed portions of the cam into registry 100 with said portion of the bolt, said depressions being located at different distances from said axis; substantially as described. 105

5. A latch including a slidable bolt; a rotatable cam, said bolt having a portion 105 movable toward and from the axis of said cam, said cam having depressions therein in which said portion of the bolt is adapted to engage; pins projecting from said cam; a spring for holding said portion of the 110 bolt in engagement with the cam; and a plunger operative to successively engage said pins and thereby intermittently move said cam to effect movement of the depressed portions of the cam into registry 115 with said portion of the bolt, said depressions being located at different distances from said axis, said cam having its approaching portions curved toward said depressions; substantially as described. 120

6. A latch including a slidable bolt; a rotatable cam, said bolt having a portion movable toward and from the axis of said cam, said cam having depressions therein in which said portion of the bolt is adapted 125 to engage; pins projecting from said cam; a spring for holding said portion of the bolt in engagement with the cam; a plunger

operative to successively engage said pins and thereby intermittently move said cam to effect movement of the depressed portions of the cam into registry with said portion of the bolt, said depressions being located at different distances from said axis; and a spring for moving said plunger in an opposite direction out of the path of said pin to permit said first spring to move the bolt 10 and said portion of the bolt to move said cam to bring another pin under said plunger; substantially as described.

In testimony whereof I have signed my name to this specification in the presence of two subscribing witnesses.
